(57) **CLAIM**

We claim an ornamental design for a projectile, as shown and described.

DESCRIPTION

This innovation is supported in part by Army Contract No. W15QKN-12-C-0015.

FIG. 1 is an isometric view of an embodiment of a projectile.

FIG. 2 is a side view of an embodiment of a projectile.

FIG. 3 is a front view of an embodiment of a projectile.

FIG. 4 is a rear view of an embodiment of a projectile.

FIG. 5 is an isometric view of an embodiment of a projectile.

FIG. 6 is a cross-sectional view of an embodiment of a projectile.

FIG. 7 is an isometric view of an embodiment of a projectile.

FIG. 8 is an isometric view of an embodiment of a projectile having a cutaway showing an inner chamber of the projectile; and,

FIG. 9 is a cross-sectional view of an embodiment of a projectile.

The dashed lines of the projectile and/or components thereof and unshaded areas within the dashed lines form no part of the claimed design.
